UNITED STATES PATENT OFFICE.

AXEL B. WALLEM, OF CYNWYD, PENNSYLVANIA, ASSIGNOR, BY MESNE ASSIGNMENTS, TO H. S. B. W.-COCHRANE CORPORATION, OF PHILADELPHIA, PENNSYLVANIA, A CORPORATION OF PENNSYLVANIA.

STEAM-TRAP.

1,347,607.

Specification of Letters Patent. Patented July 27, 1920.

Application filed May 27, 1919. Serial No. 300,041.

To all whom it may concern:

Be it known that I, AXEL B. WALLEM, a citizen of the United States of America, residing at Cynwyd, in the county of Montgomery, State of Pennsylvania, have invented certain new and useful Improvements in Steam-Traps, of which the following is a true and exact description, reference being had to the accompanying drawings, which form a part thereof.

The general object of my present invention is to provide an improved float actuated steam trap characterized by its simplicity in construction and reliability in operation and by the relatively low cost of manufacture made possible by the simplicity of its construction and comparatively small bulk.

The various features of novelty which characterize my invention are pointed out with particularity in the claims annexed hereto and forming a part of this specification. For a better understanding of the invention, however, and of the advantages possessed by it, reference should be had to the accompanying drawings and descriptive matter in which I have illustrated and described a preferred embodiment of my invention.

Of the drawings:

Figure 1 is a front elevation with a portion of the trap broken away and in section.

Fig. 2 is a section on the broken line 2—2 of Fig. 1, but with the movable parts of the trap shown in a different position in Fig. 2 than that occupied by them in Fig. 1, and

Fig. 3 is a partial section on the lines 3—3 of Fig. 2.

The trap comprises a casing consisting of a main casing part A open at one side, and a cover part A' secured to the casing body by bolts H. The casing interior is divided into an inlet chamber A², occupying the greater portion of the interior of the casing, and an outlet chamber A³, separated by the partition wall A⁴, which is an integral portion of the main casing part A. An outlet port A⁵ opens from the outlet chamber A³, and an inlet port A⁶ opens to the inlet chamber A². The partition wall A⁴ comprises two spaced apart portions parallel to the division plane between the casing body A and the cover A', spaced apart from one another

and from the adjacent side walls of the chamber A².

Alined holes A⁷ and A⁸ are formed in the parallel portions of the partition wall A⁴. These holes snugly receive the ends of the valve seat member B, which is in the form of a tubular body with peripheral ports B', and is formed at its outer end with a collar 60 or enlargement B², which abuts against the corresponding portion of the partition wall A⁴, and is secured to the latter wall by screws.

The valve C is tubular and comprises a body portion fitting in the body of the valve seat member B. The valve C is formed at its outer end with an enlargement or flange portion C', which abuts against the corresponding end of the valve seat member B. 70 The valve member C is formed with peripheral ports C², moved into and out of register with the valve seat ports B' by the oscillation of the valve in its seat. Secured to the flange end of the valve C is the spider 75 like end D' of the float arm D. As shown, the arm D is secured to the end of the valve C by screws. At its opposite end the arm D is secured to the float E. Advantageously the arm D is offset to bring the float end of 80 the arm close to the central plane of the trap. Advantageously, as shown, the partition A⁴ is provided with a projection A⁹ engaged by the arm D to arrest the downward movement of the arm when the valve 85 C is in its closed position.

The casing section A' is formed with a surface A¹⁰ which abuts against the outer end of the valve C, or rather as shown with a projection formed on the spider portion 90 of the arm D coaxially with the valve member C, and thereby prevents displacement of the valve member C. Advantageously, I provide means for positively holding the trap valve in its open position. As shown, 95 the means for this purpose comprise a shaft E⁴ journaled in the casing section A', and provided at its inner end with a crank pin E' normally out of the path of movement of the arm D, but adapted to be moved into 100 engagement with the latter and to turn it into its valve open position, as shown in Fig. 2, when the shaft E⁴ is rotated. To rotate the shaft E⁴ a handle E² is secured

to its outer end. Leakage through the wall of the trap, along the shaft E⁴, is prevented by the stuffing box F. A counter weight E³ normally holds the crank pin E' out of the

5 arm D.

It will be apparent to those skilled in the art that the trap construction described, while very simple and relatively inexpensive to manufacture, is reliable and effective.

- 10 In normal operation the valve member C is below the water level in the trap so that the valve is water sealed, thus permitting a looseness of fit insuring a minimum of frictional resistance and liability of the valve 15 sticking in its seat without giving rise to objectionable leakage under the moderate pressure conditions for which the trap is especially designed. The construction permits of a float of ample size to insure a desirably positive action while keeping the bulk and weight of the trap as a whole desirably small. The means provided for holding the valve in its wide open position, regardless of the accumulation of water in 20 the trap are simple and easily operated. The trap may be quickly and easily taken apart for cleaning, inspection and repairs. The valve is perfectly balanced against the fluid pressure and the construction employed 25 permits the valve and valve seat ports to be made desirably large.

While in accordance with the provisions of the statutes I have illustrated and described the best form of my invention now 30 known to me, it will be apparent to those skilled in the art that changes may be made in the form of my invention without departing from its spirit, and that some features of my invention may sometimes be used to advantage without a corresponding use of 35 other features.

Having now described my invention, what I claim as new and desire to secure by Letters Patent, is:

- 40 45 1. A steam trap comprising inlet and outlet chambers having a casing made up of two separable cast sections, and having its out-

let chamber formed in and integral with one of said sections by a wall projecting into the inlet chamber portion thereof, and comprising two oppositely lying wall portions through which alined horizontal openings are formed, in combination with a horizontal tubular valve seat member having its ends received in said opening, and formed with 50 ports between its ends, a tubular valve mounted in said valve seat member and a float in the inlet chamber connected to said valve.

2. A steam trap comprising inlet and outlet chambers having a casing made up of two separable cast sections, and having its outlet chamber formed in one of said sections by a wall projecting into the inlet chamber portion thereof, and comprising two oppositely lying wall portions through which alined openings are formed, in combination with a tubular valve seat member having its ends received in said opening, and formed with 55 ports between its ends, a tubular valve mounted in said valve seat member and a float in the inlet chamber connected to said valve.

3. A steam trap comprising inlet and outlet chambers having a casing made up of two separable cast sections, and having its outlet chamber formed in and integral with one of said sections by a wall projecting into the inlet chamber portion thereof, and comprising two oppositely lying wall portions through which alined horizontal openings are formed, in combination with a horizontal tubular valve seat member having its 60 ends received in said opening, and formed with ports between its ends, a tubular valve mounted in said valve seat member, a float in the inlet chamber connected to said valve, and a mechanical device for raising the float 65 and opening the valve secured to the separable section of the casing and removable with it.

AXEL B. WALLEM.
